Patented July 22, 1919.

FIG 4 INVENTOR
Harry A. Adams
John Phelps Ward
ATTORNEY

UNITED STATES PATENT OFFICE.

HARRY ALEXANDER ADAMS, OF NEW YORK, N. Y., ASSIGNOR TO SERVICEABLE INVENTIONS CORPORATION, OF NEW YORK, N. Y., A CORPORATION OF NEW YORK.

LABEL-VENDING MACHINE.

1,310,592.

Specification of Letters Patent.

Patented July 22, 1919.

Application filed June 9, 1917. Serial No. 173,839.

To all whom it may concern:

Be it known that I, HARRY ALEXANDER ADAMS, a citizen of the United States, and resident of the borough of Manhattan, city, 5 county, and State of New York, have invented certain new and useful Improvements in Label-Vending Machines, of which the following is a specification.

The label referred to in this specification 10 is a strip of paper or other flexible material, the reverse side of which is gummed. The faces of such labels are usually printed, and by the term label I will refer generally to such labels as are used by druggists, for mailing purposes and for any and all purposes where printed labels are used, and therefore, the size of my device may be varied at will.

The principal objects of the invention are to provide means for delivering one label at 20 a time from a container, and for moistening the gummed side of the label automatically during the delivery.

A further object of the invention is to provide means whereby a supply of labels may 25 be retained in the magazine ready for delivery, and an important object is the means by which the labels are retained in a flat condition and are prevented from curling or rolling as they will usually do when left exposed 30 to the atmosphere.

The construction and operation of my device will be set forth as the specification progresses.

The following is what I consider a good 35 means of carrying out this invention and the accompanying drawings should be referred to for a complete understanding of the specification which follows:

In the drawings:—

40 Figure 1 shows a side elevation of a complete device.

Fig. 2 a sectional view.

Fig. 3 a plan view of the case with the container removed.

45 Fig. 4 a plan view of the completed device as shown in Fig. 1.

Similar reference numerals indicate like parts in all of the figures where they appear.

50 The portion of my device which I may term a cabinet or container consists of an oblong box member set on end, and having a supporting base 1, which may be of wood or metal or any other desirable material. The 55 box member consists of four sides. The top

is open except for the closing means that will later be described, and the bottom is closed by the base 1. I indicate at 2 the entire box member or container, or cabinet as it may be termed, and in the sides of this member 2 I 60 arrange finger recesses 3 and 4.

Arranged within the cabinet or box member 2, is a metallic member 5, oblong in shape, and fitting at one end or the narrowest side of the cabinet 2. This metallic mem- 65 ber is deep and is provided with recesses or grooves entering from the upper, the open end, and into which I arrange the pintles or axis 6, of a revoluble roller 7. This roller is the dampening means for the label, and 70 therefore, within the member 5, and impinging upon the under side of the roller I arrange felt or other suitable material 8, which has been thoroughly dampened, or I may pour water in upon the felt 8 when it is in 75 position, allowing the water to closely approach or even reach the roller 7, as shown in Fig. 2.

The member 5 should be secured in the cabinet 2, in any suitable manner, which will 80 allow the roller 7 to project slightly upon the top, the normally open end of the cabinet 2.

A member which I may term a label magazine may be formed independently of the 85 cabinet 2, and this member is also constructed as an oblong box, the lower end of which is closed by means of a block 9, having recesses into which I introduce metallic cylinders 10 and 11. The top 17 of the magazine is secured to the members 21 and 22 which form the narrower sides of the magazine and to the member 23 which closes the back of the magazine. In each of these cylinders 10 and 11 I arrange a spring 12, which bears against 90 the lower end of the cylinder or block 9, and the upper end of which bears upon a second cylinder 13 or 14, which is movable in the cylinders 10 and 11. The springs 12 urge the cylinders 13 and 14 upward and out- 100 ward.

The cylinders 13 and 14 are connected together by means of a platform 15, to which these cylinders are secured, and upon the platform 15 I place my labels 16.

The springs 12 urge the platform 15 and labels 16 upward against the top 17 of the magazine, and a pointed screw or pin 18 passes into or through the first one or two labels for a purpose that shall appear later. 110

In Fig. 4 I show the top member 17 in plan view, and it will here be observed that I provide a finger recess 19 in this member, extending longitudinally of the member. Through 5 this recess 19 the topmost label is exposed.

To remove the label from the magazine the finger is inserted through the recess 19 and drawn toward the roller 7. This will cause the topmost label to pass outward through 10 the space 20, between the top 17 and the magazine and the adjacent side thereof. The label will pass over the roller 7, and revolving the roller the label will become moistened.

15 To add water to the member 5 it is only necessary to lift out the roller 7.

To place labels in the magazine it is only necessary to remove the magazine by placing the fingers in the finger recesses 3 and 4, and 20 by a slight pull remove the magazine as a complete unit, and then pressing down the platform 15, labels may be introduced between the platform 15 and the top 17. When the labels are in position the pressure on the 25 springs 12 is released and the platform 15 retains the labels in the position shown.

It will be noted that the screw or pin 18, punctures the topmost labels and this insures the delivery of one label at a time, as 30 it will require a sufficient pressure to draw the topmost label from the pin to insure that the first label will be separated from the second.

Modifications may be made within the 35 scope of the appended claims without departing from the principle or sacrificing the advantages of the invention.

Having carefully and fully described my invention what I claim and desire to secure by Letters Patent is:—

40 1. A label vending machine comprising a moistening means and in combination therewith a magazine having a movable plat-

form, a plurality of cylinders arranged in pairs telescoping into each other, and a 45 spring within one cylinder of each pair and adapted to urge said cylinders away from each other to elevate said platform and retain said labels under spring tension.

2. A label vending machine comprising a 50 cabinet, a moistening device consisting of a reservoir and a roller contained therein, and a label retaining means comprising a magazine having a top member provided with a finger recess and a pin entering through 55 said top member, a platform for supporting the labels, a plurality of cylinders arranged in pairs and a spring in one cylinder of each pair for urging said platform toward the delivery point for said labels, all combined for 60 joint operation as and for the purpose set forth.

3. A label vending machine comprising a cabinet a tubular metallic member arranged in said cabinet and having one of its ends 65 closed and the other end slotted, a roller mounted in said slots and a wick in said tube and impinging upon said roller, in combination with a magazine formed independently of said cabinet and arranged 70 therein, said magazine having a movable platform, springs for moving said platform, telescoping cylinders surrounding said springs, a block in said magazine for retaining the stationary portion of each said cylinder and a top for said magazine spaced away from said roller said top being provided with a slot through which the labels in said 75 magazine may be moved all combined for joint operation as herein set forth.

80 Signed at New York city, county and State of New York this 31 day of May, 1917.

HARRY ALEXANDER ADAMS.
